US0D1007789S

(12) **United States Design Patent** (10) **Patent No.:** **US D1,007,789 S**
(45) **Date of Patent:** **** Dec. 12, 2023**

(54) **ANIMAL TRAINING CLICKER**

(71) Applicant: **Zerong Yang**, Shanxi (CN)

(72) Inventor: **Zerong Yang**, Shanxi (CN)

(**) Term: **15 Years**

(21) Appl. No.: **29/913,916**

(22) Filed: **Oct. 11, 2023**

(51) LOC (14) Cl. **30-99**

(52) U.S. Cl.

USPC **D30/199**

CLAIM

The ornamental design for an animal training clicker, as shown and described.

DESCRIPTION

FIG. 1 is a front and top perspective view of an animal training clicker, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view thereof, shown in an alternative position.

The broken lines in the figures depict portions of the animal training clicker that form no part of the claimed design.

1 Claim, 9 Drawing Sheets
